UNITED STATES PATENT OFFICE

122,112

DESIGN FOR A CLOCK

Elof L. Carlson, Bristol, Conn., assignor to The E. Ingraham Company, Bristol, Conn., a corporation of Connecticut

Application June 11, 1940, Serial No. 92,925

Term of patent 14 years

To all whom it may concern:

Be it known that I, Elof L. Carlson, a citizen of the United States, residing at Bristol, in the county of Hartford, State of Connecticut, have invented a new, original, and ornamental Design for a Clock, of which the following is a specification, reference being had to the accompanying drawing, forming a part thereof.

In the accompanying drawing:

Figure 1 is a front view of a clock incorporating the design herein;

Fig. 2 is a side view of Fig. 1;

Fig. 3 is an inverse bottom view; and

Fig. 4 is a section view taken on the line 4—4 of Fig. 3.

The dominant characteristics of applicant's design reside in a base shown in full lines in which the forwardmost portion thereof is of such width that it extends but slightly to either side of the numeral "6" of a clock supported thereon and then tapers rearwardly and outwardly therefrom.

The design is further characterized by the fact that the forward portion is of such height that it extends above the lower edge of a clock supported thereon.

I claim:

The ornamental design for a clock, substantially as shown and described.

ELOF L. CARLSON.
